UNITED STATES PATENT OFFICE.

THEODORE C. MERZ, OF DETROIT, MICHIGAN.

CAPSULE-JOINING MACHINE.

SPECIFICATION forming part of Letters Patent No. 326,578, dated September 22, 1885.

Application filed June 1, 1885. (No model.)

To all whom it may concern:

Be it known that I, THEODORE C. MERZ, a citizen of the United States, residing at Detroit, in the county of Wayne and State of Michigan, have invented certain new and useful Improvements in Devices for Joining the Parts of Gelatine Capsules; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My present invention relates to the means employed for joining together the parts of a gelatine capsule—viz., its cap and body; and my invention consists in the novel means employed, as hereinafter set forth, and pointed out particularly in the claims.

20 In the drawings forming a part of this specification, Figure 1 is an isometrical view of my invention. Fig. 2 is a transverse section in elevation. Fig. 3 is a cross-section through the joining-plates on dotted line of Fig. 4. Fig. 4 is a face view of the joining-plates.

25 This machine consists of the base or table A, to which I attach firmly two upright supports, B, provided with a groove or recess, h. I locate in said grooves a spring, d. Within the grooves h, I insert freely the plates C C'. The plate C is provided with a series of holes, a, sufficiently large and long enough to receive readily the capsule body or bodies e. (See Fig. 2.) The plate C has also a corresponding number of holes, i, of a larger diameter than the holes a of plate C. The holes i are adapted to receive and hold the caps O of the capsules. (See Fig. 2.)

30 Passing horizontally through the uprights B is a supporting-bar, E, provided with heads L. Said bars are secured firmly to the uprights B, passing through the sliding or reciprocating sides D D'. The lower edges of the sides are slightly above the face of the base A, as shown in Fig. 2. Attached to the sides are metal braces n, which are bent outward, and through said braces I pass the rods E. By this arrangement the sides are held in a vertical position and prevented from tipping as said sides are forced toward and from each other, as

hereinafter set forth. Passing through the side D is a series of pins, c, having their outer ends slightly enlarged. Said pins are fitted loosely within said plates. Their free ends are 55 concaved at r. (See Fig. 2.) I attach to the outer face of said side a series of bow-springs, s. The ends of said springs press upon the heads of the pins c, as shown in Figs. 1 and 2. The pins c are made sufficiently small to freely enter the holes a of the joining-plate C, and are made to register with said holes. The side D' is also provided with pins c', like those of plate D, except said pins are firmly attached to the plate and are made 60 to register with the holes i of plate C. The plates C C' are each provided with a locking-pin, h', and hole, h² for securing said parts together, in the manner and for the purposes hereinafter set forth. The sides of the machine are provided with handles g.

65 The operations of the machine are as follows: The sides D D' are grasped by the handles g and moved back to the position of Figs. 1 and 2. The plate C, containing the 70 capsule-bodies within the holes a, and plate C', containing caps of the capsules in the holes i, (said parts of capsules being placed therein by suitable means,) are joined with their faces against each other, the sides joining having the open ends of the parts of the capsules, as shown clearly in Fig. 2. As said plates meet the pin h' of each plate enters the hole h² of the other plate, thereby locking said plates together. (See Fig. 3.) 75 The pins h' and holes h² are so arranged that when locked the peripheries of the capsule-bodies are brought within the peripheries of the caps of said capsules, also bringing the open end of the caps O against the face of the 80 plate C, containing the capsule-bodies, as clearly shown in Fig. 2. The joined plates C C' are then placed within the recesses h of the supports B, the springs d pressing said plates together. (See Figs. 1, 2, and 3.) The side 85 D' is advanced toward the plate C', causing the series of pins c' to enter the series of holes i and press upon the caps O. (See Fig. 2.) The side D is then advanced toward the plate C, causing the pins c to enter the holes a of 90 said plate, coming in contact with the closed end of the capsule-bodies e, and as said plate 95 100

is advanced, the capsule-bodies *e* are forced forward, entering the open ends of the caps, thus joining the parts of a capsule or capsules. When said parts are properly joined, the side 5 *D'* is released, when the side *D* is advanced, causing the side *D'* to move back and the joined capsules are forced out through the plate *C'*, as clearly shown at bottom of Fig. 2. The capsules falling through the opening *H* 10 are gathered in a box or like receptacle. When the capsules have been discharged, the side *D* is drawn back to former position ready to repeat the operation.

In the joining of the parts of a capsule 15 should a body, *e*, get caught while entering the cap *O*, the spring *A* will yield or be forced back, as shown in dotted lines of Fig. 2, thereby allowing the rest of the capsules to be properly joined together without interference. 20 The curvature *r* at the ends of the pins *c c'* is coincident with that of the closed ends of the capsules, thereby forming an even bearing, fitting freely over the parts.

Having thus fully set forth my present invention, what I claim as new, and desire to secure by Letters Patent, is—

1. In a device for joining the parts of gelatine capsules, the combination of the plates *C* *C'*, each plate having a series of holes for re-

ceiving the parts of capsules, and means for 30 locking said plates together face to face, whereby the open ends of the caps *O* are brought against the face of the plate *C*, containing the capsule-bodies *e*, as specified, and a series of pins or plungers attached to the 35 sides *D D'* and adapted to enter the holes of the plates to join and discharge said capsules, substantially as specified.

2. In a device for joining the parts of gelatine capsules, the combination of the base 40 provided with uprights having springs *d*, adapted to press together the plates *C C'*, the rods anchored to said uprights, said rods supporting the sides *D D'*, the side *D'* supporting a series of pins, *c'*, adapted to enter the holes 45 *i* of plate *C'*, the side *D* having a series of pins, *c*, adapted to enter the holes *a* of plate *C*, and the series of springs *s*, engaging with the ends of the pins *c*, said sides adapted to be advanced toward and from each other, as and 50 for the purposes specified.

In testimony whereof I affix my signature in presence of two witnesses.

THEODORE C. MERZ.
